PISTON FOR DEEP-WELL PUMPS.

1,369,339.

Specification of Letters Patent. Patented Feb. 22, 1921.

Application filed March 24, 1919. Serial No. 284,694.

To all whom it may concern:

Be it known that we, GRANVILLE A. HUMASON, SAM F. BASHARA, and PAUL J. BARRACO, all citizens of the United States, residing at 5 Houston, Harris county, Texas, have invented a certain new and useful Improvement in Pistons for Deep-Well Pumps, of which the following is a full, clear, and exact description, such as will enable others skilled in the 10 art to which it appertains to make and use the same.

Our invention relates to an improvement in pumps for use in deep well pumping and is especially adapted for use in pumping oil 15 or water which has therein a quantity of sand or earth and particles of grit which act to cause excessive wear in the operating parts of the structure.

In deep well pumping, and especially in 20 the pumping of oil, quantities of sand are usually mixed with the liquid, and in the operating of the pump this sand finds entrance around the piston and between the same and the inner surface of the working 25 barrel thus causing excessive wear, both in the plunger and in the working barrel, so that a tight fit, which is necessary for the operation of the pump, cannot be long maintained.

30 One object of our invention is to provide a novel construction of piston or plunger for use in deep well reciprocating pumps wherein the said plunger automatically adjusts itself for wear so as to maintain a tight fit 35 between the same and the working barrel for a long period of time.

Another object is to construct a piston on 40 the outer surface of which is an expanded collar adapted to maintain itself constantly in close contact with the inner surface of the working barrel of the pump.

Another object is to provide means for 45 expanding the collar positively when desired, so that when the collar becomes worn, it may be so adjusted as to still maintain a tight closure between the piston and working barrel.

50 Other objects in strength and durability will more clearly appear in the specification which follows and will be pointed out with more particularity in the claims hereto appended.

In the drawings forming a part of this specification, and in which like parts are

designated by like numerals throughout the 55 several views, Figure 1 is a longitudinal section illustrating our invention fitted within the working barrel of a pump, the collars being shown on a plane similar to 6-6 in Fig. 7. Fig. 2 is a transverse section thereof 60 taken on the plane 2-2 of Fig. 1. Fig. 3 is a view partly in central longitudinal section illustrating the lower end of the plunger with the valve and expanding collar in different positions. Fig. 4 is a bottom plan 65 view of our plunger fitted within the working barrel of the pump, the working barrel being shown in section. Fig. 5 is a side elevation of our improved pump plunger fitted within the working barrel of a pump, the 70 working barrel being shown in central longitudinal section. Fig. 6 is a central longitudinal section of a second embodiment of our invention taken on the line 6-6 of Fig. 7. Fig. 7 is a transverse section thereof on 75 a line 7-7 of Fig. 6. Fig. 8 is a central longitudinal section of another embodiment of our invention, the central shaft of the plunger being shown in elevation for greater 80 clearness and the collars cut on a plane similar to 6-6 of Fig. 7. Figs. 9 and 10 are profile views showing the central faces of two different sections of my expanding collar.

With special reference to Figs. 1, 3, and 85 5, I have shown my improved pump plunger 11 connected to the lower end of a sucker rod 12 of ordinary construction threaded as shown at 13 for coupling with the next upper section thereof. The plunger portion of the rod is cylindrical in shape and is fitted with one or more expanding collars 14, 14' for the purpose of maintaining a 90 tight contact between the said plunger and the outer working barrel 15 of the pump. These collars, of which I have shown two in 95 Figs. 1 and 5, are so arranged as to be pressed automatically outward into contact with the working barrel. Each collar is split longitudinally into four sections. The adjacent sections are of unequal formation, 100 one of them being wider at the bottom and narrower at the top, while the adjacent one is wider at the top end and narrower at the bottom. A line of division 16 between the sections is therefore slightly inclined as 105 shown in Figs. 5, 9, and 10.

The inner body 17 of the plunger is provided with a beveled recess in which the four

sections of the collar are adapted to fit. With special reference to Fig. 1, the upper collar is fitted within a recess tapered inwardly at the upper end as shown at 18, and 5 having a central cylindrical portion 19 and a second outwardly flaring surface 20 somewhat shorter in length than the surface 18 and second cylindrical surface 21, this surface terminating at its lower end in an 10 abrupt shoulder 22 separating the cylindrical surface 21 from a second surface 23 reduced in diameter to correspond with that of the surface 19. Between the cylindrical surface 23 and a second lower cylindrical recess 15 is a larger cylindrical member 24 of such diameter as to fit closely within the working barrel of the pump. The lower collar 14' is of the same formation as the upper collar, being shown reversed, however, 20 in direction, the part corresponding to the lower end in the upper collar being placed at the upper end on the lower collar. Both collars, however, may be turned in the same direction as will be obvious.

25 The four separate sections of the collar are maintained in position upon the tapered surfaces just described by means of a resilient ring or spring 25 fitted within a groove 26 in the outer periphery of the 30 said sections. This groove is wider than the ring which fits therein so as to allow a longitudinal movement of the sections relative to the resilient retaining ring or spring 25. This ring is similar in formation to an ordinary piston ring and is split in one place, as shown at 26' in Fig. 5, to allow a 35 limited expansion and contraction thereof. Said ring may be replaced by a spiral spring 27 fitted within the slot 26, such a spiral 40 spring being shown on the lower collar 14.

As previously stated, one of the sections is somewhat wedge-shaped with the wider end up and the adjacent one is likewise 45 wedge shaped with the wider end downward. The sections having the wider end downward are adapted to be forced upwardly on the plunger while the adjacent one is adapted to be forced downwardly on the tapered surface of the plunger. With 50 reference to the upper collar 14 of Fig. 1 the section at the left of the said collar is adapted to be forced downwardly and to obtain this result a small hole is bored upwardly in the tapered portion 18 of the 55 plunger to form a seat for a small helical spring 29. The lower end of this spring is adapted to seat within a similar hole or recess in the cooperating tapered surface of section 28. The adjacent section 30, shown 60 at the right hand side of Fig. 1, is adapted to be forced upwardly, this being accomplished by a small leaf spring 31 attached to the lower end of the section 30 and bearing between the same and the adjacent 65 shoulder formed by the member 24. The

lower end of section 30 is cut away on its inner surface to provide a recess 32 sufficient to allow the upward movement of this section relative to the shoulder 22 on the plunger. 70

It will be noted that the movement vertically of any of the sections of the collar will cause the same to be forced outwardly, due to the fact that the sections are adapted to slide upon the outwardly tapered surfaces 18 or 20 of the plunger. When the section 28 is forced downwardly by the spring 29 it will be forced outwardly by the tapering surface 20 on which it is adapted to slide. When the adjacent section 30 is 75 forced upwardly by the spring 31 it will be projected outwardly by the sliding of the collar upon the surface 18. By this means any wear upon the surface of the collar will be automatically taken up by the expanding of the collar caused by the springs 29 and 31. Due to the fact that these sections are wedge shaped, the movement of the adjacent sections in opposite directions will 80 maintain the adjacent edges of the sections 85 constantly in close contact with each other, thereby preventing the formation of longitudinal slots or spaces through which water or air might escape. This sort of collar will, therefore, automatically maintain itself 90 expanded into contact with the working barrel of the plunger and will also automatically maintain a tight contact between the adjacent edges of the collar either when contracted, as shown in Fig. 1, or when expanded, as shown in Fig. 3. The lower collar 14' is adapted to function in exactly the 95 same way as the upper collar 14 and no particular description thereof will be necessary; and while two expanding collars are 100 shown on the plunger disclosed in this drawing, it is obvious that one collar may be used alone or that several collars may be used as found most convenient and efficient for the work at hand. 105

The lower end of our plunger, below the expanding collars, is of the full outside diameter of the plunger, as shown at 33, and is recessed interiorly to provide a valve chamber 34. The lower end of this chamber is threaded at 35 to receive a plug 36 closing the lower end of said chamber. This plug is bored longitudinally to provide a central opening in which a valve stem 37 is adapted to reciprocate. The lower end of 110 the opening, through which the valve stem passes, is enlarged in diameter at 38 to accommodate a cylindrical nut 39 on the lower end of the stem, said nut being adapted to contact with the upper shoulder of said recess 38 to limit the upward movement of valve stem. At the upper end of this stem is a head flared outwardly therefrom to form a frusto-conical valve member 40 fitting within a conical seat 41 in the upper 115 120 125 130

end of the plug 36. Below the seat 41 the plug is recessed cylindrically to form a shallow chamber 42, from which lead the four outwardly inclined channels 43 connecting 5 the chamber 42 with the lower face of the plug.

The valve chamber 34 is reduced in diameter above the valve and leads into an upwardly extending channel 44 centrally of 10 the plunger. This channel terminates adjacent the upper end of the plunger and, from this upper end, outwardly inclined passages or ducts 45 serve to conduct the liquid from the channel out the upper end of plunger. 15 The four ducts 45 terminate in an annular inwardly tapered valve seat 46 closed ordinarily by a valve member 47. This valve member is annular in shape, closely surrounding the sucker rod 12 and adapted to 20 be retained in the tapered seat 46 by gravity. The upper face of the valve ring 47 is tapered outwardly from the sucker rod 12 so as to prevent the packing of sand around the upper end thereof.

25 In order to further prevent the lodging of sand and other sediment above the valve 47 the sucker rod 12 may be hollow, as shown at 12' in Fig. 6, and from the hollow central portion thereof inclined channels 48 30 may be so placed as to provide passages for flushing water to clean the upper surface of the valve from accumulations. Water pumped downwardly through the hollow sucker rod will be projected with force 35 against the upper surface of the valve member 47 and maintain the same constantly free from accumulation of matter.

As shown in Fig. 6 a lower valve 40 may be dispensed with and free upward passage 40 through the central channel 44 be thereby provided. The valve member 47 will thereby serve to handle the upward discharge of the water through the plunger on the downward stroke thereof and will close during 45 the upper stroke to force the oil or water to the surface.

In order to prevent the rotation of the sections of the collar 14 and 14' upon the plunger, which rotation might tend to mutilate the springs 29, one of these sections, such as the section indicated at 50 in Fig. 7, 50 may be provided with an inwardly extending key 51 fitted within a slot or recess in the central barrel of the plunger. This key 55 is adapted to slide vertically within the slot when the collar is expanded, but will prevent lateral movement of this section and thereby prevent rotation of the collar. A slight lateral movement of the other sections will take place, due to the wedge shaped formation of the said sections, when the collar is expanded.

In Figs. 8 to 10 inclusive we have shown a means of positively expanding the collars 5 fitted upon the plunger. With special ref-

erence to the upper collar shown in Fig. 8, we have shown the said collar 14^a with a threaded engagement with the central barrel of the plunger. The section which is adapted to be expanded upwardly is threaded 70 at 52 for co-operation with a spiral channel 53 upon the cylindrical surface 19^a of the plunger. The opposite section 28^a adapted to be moved downwardly, is slidable upon the threaded central portion 19^a and 75 is threaded at 55 into engagement with a spiral channel 54 in the cylindrical surface 23^a of the plunger. Thus the section 30^a will slide upon the surface 23^a and will be held in threaded engagement with the surface 19^a while the adjacent section 28^a will slide upon the surface 19^a and be given a positive upward or downward movement by means of its engagement to the threaded 80 channel 54 of the pump plunger. The other 85 elements of this pump plunger are intended to be identical with that shown in the previous embodiment with the exception of the fact that the springs 29 and 31 may be dispensed with and the sliding key 51 is eliminated.

When it is found that the collars of the plunger are being worn the sucker rod 12 of said plunger is given a right-handed rotation. This rotation of the sucker rod, and the plunger barrel attached thereto, will serve to move two of the sections of each of the collars upwardly and the two intermediate sections will be forced downwardly, thereby expanding the collar, as previously 95 explained, and maintaining the sections thereof in close contact. In order that one section may be forced upwardly and the other downwardly, the two spiral channels 53 and 54 are cut in opposite directions 100 upon the plunger barrel. By this means the rotation in one direction of the said barrel will force two sections in one direction and the adjacent or intermediate two in the opposite direction.

In the operation of our invention, the expanding collar may be made of hard material, such as steel, thereby serving to resist wear to the best advantage. But when sand or similar material finds entrance 115 around the plunger and between the same and the working barrel causing wear upon the adjacent parts, the collars shown in Figs. 1 to 7 inclusive are automatically expanded 120 to take up this wear and thereby serve to maintain a tight fit between the plunger and the working barrel at all times. In the embodiments shown in Figs. 8 to 10 inclusive, when wear occurs so that it is noted that the pump is not functioning properly, a slight 125 turn or partial turn of the sucker rod, and the plunger barrel attached thereto, will serve to tighten the collars against the inner surface of the working barrel to again maintain the close contact necessary for proper 130

- and efficient operation. It will be obvious that a limit will be reached, especially in this modification, whereby further expansion of the collars will be prevented, due to 5 the fact that the collar will be expanded to such an extent that the threaded engagement between the collar and the barrel of the plunger will be no longer maintained. A new collar will then be required.
- 10 Having thus described our invention, the advantages and objects of which will be apparent without further explanation, what we claim is new and desire to protect by Letters Patent is:
- 15 1. In a pump, the combination of a working barrel, a plunger reciprocatable therein, a collar thereon longitudinally divided into a plurality of sections, means to retain said collar in assembled position on said plunger, 20 means to automatically expand said collar, and means to retain said sections constantly in close contact with each other.
2. In a pump, the combination of a working barrel, a plunger reciprocatable therein, 25 a collar on said plunger longitudinally divided into a plurality of sections, said collar fitted within an outwardly beveled recess on said plunger and means to force alternate sections of said collar in opposite directions 30 and thereby expand same into close contact with said working barrel.
3. In a pump, the combination of a working barrel, a plunger reciprocatable therein, a collar on said plunger divided longitudinally 35 into a plurality of sections, alternate sections of said collar being tapered longitudinally in opposite directions, and means adapted to force said sections constantly into close contact within each other.
- 40 4. In a pump, the combination of a working barrel, a reciprocatable plunger, an expanded collar thereon divided longitudinally into a plurality of sections, said sections being tapered alternately in opposite 45 directions, means to hold said sections in assembled position and means to force said sections alternately in opposite directions to wedge the same apart and maintain a close contact between the same.
- 50 5. In a pump, the combination of a working barrel, a plunger therein, a collar on said plunger divided longitudinally into a plurality of sections, means to expand said collar, and means to retain the sections of

said divided collar in constant contact with 55 each other along their entire adjacent edges.

6. In a pump, the combination of a working barrel, a plunger reciprocatable therein, a split collar on said plunger comprising a plurality of sections, said collar fitting 60 within a tapered recess on said plunger, means to positively force the alternate sections of said collar in opposite directions actuated by the rotation of said plunger.

7. In a pump, the combination of a working barrel, a plunger therein, oppositely beveled surfaces on said plunger, a collar thereon adapted to fit upon said surfaces and divided longitudinally along diagonal planes into a plurality of sections, means to 70 force alternate sections in opposite directions, whereby the collar is expanded and the sections maintained in contact at all times.

8. In a pump, the combination of a plunger, an expanding collar thereon comprising several sections tapered alternately in opposite directions and means to maintain the adjacent edges of said sections constantly in contact. 75

9. In a pump, the combination of a plunger, an expanding collar thereon comprising a plurality of longitudinal sections tapered alternately toward opposite ends thereof, means to force said sections constantly into contact with each other and means to retain said sections on said plunger. 80

10. In a pump, the combination of a plunger, a collar thereon divided longitudinally by inclined planes into a plurality of sections, coöoperating surfaces on said plunger and said collar to expand said collar when said sections are forced alternately in opposite directions and means adapted to force said sections in the direction desired. 85

11. In a pump, the combination of a plunger, a collar thereon divided longitudinally into a plurality of sections, and having a threaded connection with said plunger and contacting beveled surfaces on said plunger 100 and collar whereby said collar is expanded by the rotation of said plunger.

In testimony whereof, we hereunto affix our signatures.
